[57] CLAIM

The ornamental design for a boot-to-binding interface for a step in snowboard binding, as shown and described.

DESCRIPTION

FIG. 1 is a top front right side perspective view of the boot-to-binding interface for a step in snowboard binding of the present invention;

FIG. 2 is a top view of FIG. 1;

FIG. 3 is a back side elevation view of FIG. 1;

FIG. 4 is a front side elevation view of FIG. 1;

FIG. 5 is a right end view of FIG. 1, the left end view being a mirror image thereof; and,

FIG. 6 is a bottom plan view of FIG. 1.

The broken lines showing the cross bars and connecting bosses of the boot-to-binding interface in FIGS. 1 to 6 are for illustrative purposes only and form no part of the claimed design.
